BASE FOR PORTABLE HOUSES

William B. Stout, Detroit, Mich., assignor, by
mesne assignments, to Stout Engineering Labo-
ratories, Inc., Dearborn, Mich., a corporation of
Michigan

Application July 30, 1937, Serial No. 156,555

3 Claims. (Cl. 72—77)

This invention relates to bases or supporting structures for expandable trailers. More particularly it relates to a permanently mounted base construction primarily designed for the purpose of providing a rigid mounting for trailers of the generic type disclosed in applicant's prior co-pending applications, Serial Nos. 49,463 and 115,180, assigned to the assignee of the present invention.

10 In order to obtain a better understanding of the nature and general object of the present invention, reference may be had to these prior co-pending applications.

It is a primary object of the present invention 15 to provide a rigid supporting base for structures of this general character which includes novel means for accurately positioning the road wheels of the trailer structure with respect to the base in order that when the structure is expanded or 20 unfolded, the base may be utilized to support the building structure in level predetermined adjusted position.

The present invention contemplates the provision of a plurality of short upwardly extending 25 rigidly mounted supports which are adapted to engage the under side of the building structure at various strategic points in order to provide a strong rigid support for the same and, in addition, means are provided for obtaining access to 30 the road wheels of the vehicle in order that the tires thereof may be deflated in order to firmly seat the building structure on the supports.

Yet another object of the present invention is 35 to provide a base for trailers of this generic type in which channels or runways are provided for receiving the road wheels of the trailer, which channels are so disposed and so constructed that they serve to provide means for accurately positioning the building structure with respect to the 40 base prior to the unfolding of the same.

Still further, the present invention contemplates the provision of a substantial base construction which, if desired, may be constructed in such a manner as to provide a cellar or base- 45 ment which may be used for storage purposes in the event that the building structure is used for living quarters during a protracted period.

Many other and further objects, advantages, 50 and features of the present invention will become more clearly apparent from a consideration of the following specification in connection with the accompanying drawings forming a part thereof.

In the drawings:

Figure 1 is a top plan view of one embodiment 55 of the present invention.

Fig. 2 is a transverse sectional view taken substantially on the line 2—2 of Fig. 1 illustrating in detail the cross sectional configuration of the structure shown in Fig. 1.

Fig. 3 is a fragmentary transverse sectional view taken substantially on the line 3—3 of Fig. 1 illustrating in further detail the construction of the improved base structure.

Fig. 4 is a fragmentary sectional view similar to Fig. 3, illustrating the base structure with an 10 expandible building disposed in unfolded condition thereon.

Fig. 5 is a perspective view of a modified form 15 of the invention, particularly adaptable to installations where a maximum of insulation is desired.

Fig. 6 is a still further modified view of the invention which has the same generic features as that disclosed in the preferred form of the invention illustrated in Figures 1 to 4, but which is 20 considerably simpler in construction.

Fig. 7 illustrates a modified form of structure 25 which may be utilized in connection with any of the foregoing forms of the invention to take the weight off the wheels of the vehicle when it is mounted in position upon the support.

As will be apparent by reference to the prior co-pending applications referred to above, the specific form of base structure illustrated in the drawings and described below is primarily designed for supporting expandible building structures of the generic type shown in elevation in Fig. 4. Building structures of this generic type include a main or central section 5 which is supported for transportation on a pair of road wheels 6 and which has associated therewith foldable walls which may be unfolded to substantially the positions shown in Fig. 4 when the building structure is stationary to provide reinforced side wall sections for the central portion of the building 40 structure when the same is transported from place to place.

The improved base construction disclosed in the drawings includes a generally rectangular structure formed of reinforced concrete or other 45 suitable material and in the form shown, has a floor 7, side walls 8, and walls 9. The top is preferably closed by a substantially horizontal reinforced concrete roof 10 having a plurality of upwardly extending supporting posts 11 adapted to engage the corners of the central section 5 of the building structure when the same is mounted in position thereon.

Adjacent the corners of the surface structure 50 55 of the base are, in addition, provided a plu-

rality of posts 12 which are adapted to engage and support the outer corners of the floor section of the building structure when the same is in unfolded condition. The structure as a whole forms 5 a hollow room-like basement or cellar immediately beneath the building structure which it serves to support and convenient access to this basement or cellar may be had by means of a series of steps 13 and a doorway opening 14. The upper surface 10 of the supporting base has a pair of parallel wheel receiving channels 15 therein which extend from one side of the surface to a point substantially in the central portion of the upper surface of the base structure. These channels become 15 substantially deeper adjacent their rear ends to provide wheel receiving recesses 16 which serve to retain the building structure in adjusted position upon the base structure.

A suitable opening 17 is provided through the 20 surface of the base structure between the wheel receiving recesses 16 in order that access from the cellar may be had to the road wheels of the trailer structure in order to deflate the tires thereof and provide proper seating of the structure upon 25 the base.

In use of the device, an expandible portable building construction in folded condition may be rolled into position upon the supporting base, the wheels of the building structure entering the 30 channels 15 and rolling rearwardly until they become seated in the wheel receiving recesses 16. The building may then be unfolded to expanded condition and the parts thereof are then occupying the positions shown in the dotted lines in Fig. 35 3. Access to the road wheels may then be had through the opening 17 from the cellar of the base structure and the tires of the road wheels may be deflated through lowering the entire building structure on to the supporting posts 11 and 12 40 where it will be rigidly seated and displacement thereof will be virtually precluded. This supporting base provides an exceptionally strong permanent mounting for the portable building construction when it is desired to locate the same in a predetermined location for a relatively long 45 length of time and it will be seen that the cellar beneath the supporting surface of the base structure will serve to provide convenient means for storing articles during the time the building structure is disposed on the base. A coping wall 50 20 may surround the portion of the base structure adjacent the wheel receiving channels in order to preclude the entrance of moisture to the cellar through the opening 17. It will be further appreciated that the floor of the building is located in slightly spaced relation with respect to the upper surface of the supporting structure in order to provide proper ventilation beneath the building and yet at the same time to provide a 55 strong rigid mounting for the trailer structure.

While the above described form of the invention will find wide, practical utility in certain installations, it has been found desirable to provide in some cases a support structure which will obtain 60 substantially equivalent results and yet at the same time be somewhat cheaper to construct. With this end in view, Figures 5 and 6 of the drawings illustrate modified forms of the base structure illustrated in Figures 1 to 4, inclusive, 65 which modified forms of base structures have substantially the same general features but depart slightly in the specific form of construction.

It will readily be appreciated that in the form of the invention illustrated in Figures 1 to 4, inclusive, relatively widely separated supporting

posts have been used for the purpose of supporting the foldable portions as well as the central portion of the collapsible building structure when the same is mounted upon the support. This form of supporting base is particularly desirable 5 for utilization during the summertime when a maximum of ventilation is desired underneath the floor of the vehicle, in order to maintain the interior temperature thereof as cool as possible. However, in certain installations, it may be desirable 10 to provide a support of the type illustrated in Figure 5, which is primarily adapted for use during cold weather and which contemplates the use of a retaining wall or foundation structure for supporting the foldable portions of the 15 collapsible building structure in such manner that the space underneath the floor of the vehicle is completely enclosed when the same is in unfolded condition and thereby provides insulation for the 20 floor of the vehicle which may aid in maintaining the vehicle warm inside.

To accomplish this end, and at the same time to provide a somewhat simpler supporting base structure, a construction substantially as shown in Figure 5 may be used, which supporting base 25 may, as has been described above, be formed of reinforcing concrete, and includes a pair of wheel receiving channels 30 spaced apart in accordance with the spacing of the wheels of the portable building structure to be supported. Adjacent 30 their rear ends, these channels are provided with depressions 31 which are adapted to accurately position the vehicle upon the support and prevent longitudinal movement thereof once the vehicle has been seated in position. A foundation or retaining wall 32 is cooperatively positioned with respect to the wheel receiving channels 30 so that as the expandible portions of the building are unfolded, this retaining wall will serve to support them and enclose the air space immediately beneath the floor of the expandible building construction. If desired, a well 33 may be formed between the wheel receiving channels, access to 35 which may be had by means of a stairway 34 in order that when the expandible building structure is disposed upon the support for a substantial 40 length of time, access to the supporting wheels of the vehicle may be had in order to deflate the tires, as has been described above in connection with the preferred embodiment of the invention. 45

In Figure 6 is illustrated a form of the invention which is very similar in many respects to that illustrated in Figure 5 and which includes wheel receiving channels 30 having recesses 31 at their inner ends and the same form a well 33 between 50 these wheel receiving channels, access to which may be had by means of the stair 34. In this form of the invention, the supporting or retaining wall is dispensed with and a plurality of posts 35 may be placed directly in the earth adjacent to 55 and cooperatively positioned with respect to the wheel receiving channels 31, which posts may be utilized for the purpose of supporting the foldable portions of the building structure when the same is in unfolded condition. This form of the invention has substantially the same generic features as the preferred form of the invention illustrated in Figures 1 to 4 of the drawings, except that it is considerably simpler and cheaper to construct and does not provide as much storage 60 space underneath the building structure.

In Figure 7 is illustrated a feature which may be used in connection with any of the above described forms of the invention and which may be utilized in order that it will be unnecessary to 75

deflate the tires of the vehicle when the same is positioned upon the support. This feature comprises the provision of a cam surface 37 which may serve to elevate the axle of the vehicle as the same is backed into position upon the supporting base, whereby the tires of the vehicle will be raised from the ground, thus taking the load off the tires of the vehicle and rendering deflation of the tires unnecessary. It will be readily appreciated that this expedient may be used in connection with any of the foregoing forms of the invention, as may be desired.

Several specific embodiments of the invention have been illustrated and described herein particularly designed and adapted for supporting a definite given type of expansible building structure, such as has been described in prior copending applications referred to above. Many modifications of the structure disclosed, which may be utilized for the purpose of supporting buildings of the various and different types, will be apparent to those skilled in the art and are included in the spirit and scope of the invention as defined in the subjoined claims.

25 What is claimed is:

1. A base structure for supporting portable buildings including in combination a relatively rigid enclosed housing having an upper surface substantially the size of the building to be supported, posts extending upwardly from said upper surface adapted to engage a portable building disposed thereon, and wheel receiving channels in said upper surface adapted to guide the wheels

of said portable building into predetermined position with respect to said posts, said wheel receiving channels being substantially deeper adjacent the rear ends in order to accurately position said portable building structure with respect to 5 said posts.

2. A base structure for supporting portable buildings including in combination a relatively rigid enclosed housing having an upper surface substantially the size of the building to be supported, posts extending upwardly from said upper surface adapted to engage a portable building disposed thereon, wheel receiving channels in said upper surface adapted to guide the wheels of said portable building into predetermined position 10 15 with respect to said posts, wheel receiving recesses in said channels and an opening through the upper surface of said base structure adjacent said wheel receiving recesses providing access thereto.

3. A base for supporting vehicular building 20 structures including in combination a substantially rectangular housing, wheel guiding channels in the upper surface of said housing, wheel receiving recesses in the end of said channels, upwardly extending supporting means adapted to 25 engage the under side of said building structure, means at one of the sides of said housing to obtain access to the interior thereof, and an opening through the upper surface of said housing providing access from the interior thereof to said wheel 30 receiving recesses.
